UNITED STATES PATENT OFFICE.

RICHARD C. WINCKEL, OF ROSELLE, NEW JERSEY, ASSIGNOR TO WESTERN ELECTRIC COMPANY, INCORPORATED, OF NEW YORK, N. Y., A CORPORATION OF NEW YORK.

TELEPHONE TRANSMITTER.

Application filed September 2, 1924. Serial No. 735,274.

This invention relates to telephone transmitters, and more specifically to a carbon button closure for confining the carbon granules to the granule chamber.

5 Prior to this invention, felt washers were used for this purpose. Such material, however, is open to the objection that due to the heating the electrodes are subjected to when in use these felt rings develop animal 10 fat which condenses in the button and coats the carbon granules with grease, thus insulating the carbon granules and preventing the proper operation of the transmitter.

The object of this invention is to provide 15 a carbon button closure which confines the carbon granules in a positive manner and which when submitted to heat is free from the objectionable release of greasy matter, characteristic of the felt washers, heretofore 20 used for carbon closures in telephone transmitters.

In accordance with this invention the carbon granules are confined in the chamber by a number of layers of thin sheet heat- 25 resisting insulating material, these sheets having perforations so that when positioned on the electrode in which the granule chamber is formed these perforations register with the outer open end of the granule 30 chamber and engage the diaphragm, thereby positively preventing the escape of the granules and at the same time forming a yieldable closure to permit the diaphragm to vibrate properly in response to the voice 35 vibrations.

The rings are preferably of paper such as is used in electric condensers and are disposed in a fan-like arrangement which permit the diaphragm to respond accurately to 40 its adjusted vibration frequency.

Other features of the invention and advantages will appear from the following description and by the claims appended thereto, reference being had to the accompanying drawings in which Fig. 1 is a sectional view of the transmitter embodying the features of this invention; Fig. 2 is a plan view of a paper ring used therein; for the carbon closure; Fig. 3 is a plan view of a transmitter embodying a modified form of carbon button closure; Fig. 4 is a sectional view thereof and Fig. 5 is a plan view of a paper disc used in the modified form of carbon button closure shown in Figs. 3 and 4.

55 The telephone transmitter in which this

invention is particularly well adapted for use generally consists of a casing 10, in which the bracket 11 is mounted and held secured against the shoulder portion 9 of the casing by means of a mouthpiece 12, which is 60 screwed on the threaded portion 13 of the casing. A diaphragm 14, held securely on the front end portion of bracket 11 by means of the mouthpiece 12 contacts with the outermost disposed ring of a paper pad formed 65 by a plurality of paper rings 15 which are disposed in a fan-like arrangement on the front portion of electrode 16 as shown in Fig. 1. The rings 15 may be made of any well-known heat resisting material, such as 70 paper of the kind used in electric condensers. These rings 15 are secured on the electrode 16 by means of a metal cap 17 spun over the periphery of electrode 16. Electrode 16 is provided with a stem 18 which fits into an 75 insulating bushing 19 disposed in the central portion of bracket 11 and a nut 20 80 screwed on the threaded end portion of stem 18 is provided for holding an incoming wire 21 and the electrode 16 securely in adjusted 85 position. The incoming wire 22 is attached to the bracket 11 by means of a screw 23, thus completing the receiver loop through the diaphragm 14 in contact with the carbon granules, as shown at 24 in Fig. 1, wherein 90 the carbon granules are shown held in position in the cup 25, which is formed by the electrode 16 and partly by the fan-like arrangement of the paper rings 15, which permit the diaphragm 14 to respond accurately 95 to its adjusted vibration frequency, while forming an efficient closure therebetween.

In the modification of the invention shown in Figs. 3 and 4, the paper discs 15 are mounted in the insulating ring 33 and have 95 a plurality of circular holes 26, 27, 28, etc., shown in Fig. 5, which register with the carbon cups 29, 30, 31, etc., in the electrode 16. The diaphragm 14 cooperates with the paper discs 15 for holding the carbon granules in the cup to form a yieldable and efficient closure between the diaphragm and the electrode 15 while permitting the diaphragm 14 to respond accurately to its adjusted frequency.

100 What is claimed is:—

1. In a telephone transmitter, an electrode having a granule chamber, sheets of thin insulating material superimposed on each other and having perforations which register with 110

each other and with the granular chamber entrance and mounted on said electrode around the entrance to said chamber, and a diaphragm contacting with the outer sheet and the granules in said chamber.

2. In a telephone transmitter, an electrode having a granule chamber, a number of rings of heat-resisting insulating material surrounding the entrance to said chamber 10 perimposed on each other and having perforations which register with each other and with the granular chamber entrance, means attached to the peripheries of said rings and electrode for binding the edges of the rings 15 to the outer edge of the electrode, and a diaphragm held in contacting relation with the free end of the outer ring and with the granules in said chamber.
3. In a telephone transmitter, the combination with an electrode, a chamber therein containing conducting granules, a diaphragm disposed in juxtaposition and in a plane parallel to said electrode, and a plurality of paper rings mounted on said electrode and disposed in contact with said diaphragm for holding the granules in said electrode.
4. In a telephone transmitter, the combination with an electrode, a chamber in said

electrode containing conducting granules, a diaphragm, and paper rings disposed in a fan-like arrangement in contact with said diaphragm for holding said granules in position in said electrodes.

5. In a telephone transmitter, the combination with a recessed electrode, carbon granules therein, a diaphragm disposed in juxtaposition to said electrode, and a plurality of paper members disposed between said diaphragm and said electrode in a manner to form a yieldable closure therebetween for holding said carbon in said electrode and to permit the free movement of said diaphragm.

6. In a telephone transmitter, the combination with a circular electrode having a cavity in its central portion, granules therein, a plurality of superposed paper rings disposed on the plane surface of said electrode and concentric with said cavity, a metal cap having a flange spun over said electrode for holding said rings in position, and a diaphragm cooperating with the rings for holding the carbon granules in said cavity.

In witness whereof, I hereunto subscribe my name this 23rd day of August A. D., 1924.

RICHARD C. WINCKEL.
